UNITED STATES PATENT OFFICE.

ARTHUR E. HOTCHKISS, OF CHESHIRE, CONNECTICUT.

CLOCK-PENDULUM.

SPECIFICATION forming part of Letters Patent No. 253,282, dated February 7, 1882.

Application filed October 8, 1881. (No model.)

To all whom it may concern:

Be it known that I, ARTHUR E. HOTCHKISS, a citizen of the United States of America, residing at Cheshire, in the county of New Haven and State of Connecticut, have invented certain new and useful Improvements in Pendulums for Clocks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to pendulums for clocks; and it consists, first, in attaching the upper end of the pendulum-rod to the verge, or to a collet on the verge-shaft, by inserting the upper end of said pendulum-rod in a recess in the side of said verge or collet, or in a perforation through the same; secondly, in perforating the side wall of the scalp or shell of the ball for the reception of the pendulum-rod; thirdly, in giving to the perforations or slots thus formed, or to one of them, and to the corresponding part of the pendulum-rod, such shape as to prevent said ball from turning on said rod; fourthly, in perforating said scalp or shell and allowing said perforation or perforations to contain a portion of the metal filling, for the purpose of fastening the scalp and filling together; and, finally, in additional details of construction hereinafter set forth.

In the accompanying drawings, Figure 1 represents a perspective view of the pendulum-rod, ball, verge, and pivot-rod or verge-shaft. Fig. 2 represents a perspective view of a modified arrangement, in which the pendulum-rod is attached to a fixed collet on the pivot-rod or verge-shaft. Fig. 3 represents a detail view of the scalp or shell. Fig. 4 represents a detail view of a modification of the shell having no filling. Fig. 5 represents a detail view of the filling or body of the ball. Fig. 6 represents a detail view of the scalp and filling. Fig. 7 represents a similar view of the pendulum-rod, and Fig. 8 represents a detail view of the verge.

The same letters indicate the same parts in the different figures.

A designates the pivot-rod or verge-shaft, provided with terminal gudgeons *aa* and verge

B, which last consists of a collet and pallets, said collet having attached to its side the laterally-extending pallets *CC*. This verge has also a recess, *b*, formed in one side obliquely below and behind its center, as shown in Fig. 8. In the modification shown in Fig. 2 the verge is left without recess, but a recess is made in the collet *Z*, which is fast on shaft *A*, which recess receives the bent upper end of rod *D*. The verge or collet may be perforated instead of being recessed, and a semicircular flange or other piece fixed to the shaft may take the place of the collet.

D designates my pendulum-rod, the upper end, *d*, of which is bent or turned laterally and inserted in the said recess or perforation of the verge or collet. Solder or any other suitable means may be used to complete the fastening.

To perforate a flat piece like a verge, collet, or flange is less troublesome than to make a recess or perforation in a cylindrical piece like a verge-shaft, so that I gain a decided advantage in cheapness and speed of manufacture. The rod and verge or collet are made independently of one another, in quantities, and easily fitted together.

I have shown a pendulum-rod bent at *D'*; but in many movements I prefer to use a straight rod of any other suitable form. The lower end of said rod is screw-threaded to receive a nut, *E*, which regulates the pendulum-ball in the usual manner. This ball consists of a shell or scalp, *G*, preferably of brass, and a filling or body, *F*, preferably of lead, cast therein. In order to conveniently attach this filling or body to the scalp without using additional fastening devices, I supply said scalp with molten metal, through holes *gg* in the side wall, *G'*, of said scalp, and allow said holes to fill with said metal, which, on hardening, forms a very secure attachment between said parts *F* and *G*. Said body or filling is then cut away at its middle part, *F'*, to leave room for the pendulum-rod and to lessen the weight of the ball; or, by using a suitable mold-cap or core in combination with said shell, the body *F* may be cast at once in its final shape. Of course the molten metal need not be poured in through holes *gg*, provided it is allowed to fill the same, producing pins *ff*, which are in one piece with said body, as shown in Fig. 4. The metal could be inserted

in the shell and perforations by other means than casting—for instance, swaging the metal while in a cold state. The annular side wall, G', of said scalp or shell is extended farther 5 than usual from the upright wall or plate thereof, and has at top and bottom, respectively, perforations or slots g' g², which have an oblong form, and receive the flattened part D³ of pendulum-rod D, that fits thereon, so as to prevent 10 the ball from turning on said rod. By passing the pendulum through the shell or scalp I obtain durable bearings therein and avoid wearing the soft material of the filling, beside lesser advantages.

15 Instead of making the holes g' g² oblong, I may make them angular, of irregular form, or one hole may be round and the other hole oblong, angular, or irregular.

The pendulum-rod at the part which is in the 20 oblong, angular, or irregular hole or holes should, of course, have a corresponding shape, or some other shape which locks with the sides of said hole or holes. Thus the holes may be square and the rod oblong in cross-section, setting into two of the angles or corners.

25 The most satisfactory form of the locking part of the rod is the flattened one shown, the edge of the flattened part being presented to the front for the sake of neatness of appearance.

I may omit the filling and the perforations for attaching the same and use a shell of thicker metal, as shown in Fig. 4, the weight of said shell being sufficient to answer as a ball for 35 said pendulum. This form of ball is easily struck up and perforated, and gives far less trouble in manufacture than the solid balls, which require to be cut through from top to bottom.

40 In place of using pins or studs in one piece with the filling, I may pass screws or other

fastenings through the perforations in the side wall to hold the said filling.

Having thus fully described my invention, what I claim as new, and desire to secure by 45 Letters Patent, is—

1. In combination with a verge, a pendulum-rod having its end bent at right angles to its length and inserted in a recess or perforation of the verge, substantially as and for the purpose set forth. 50

2. A pendulum-ball consisting of a perforated scalp or shell and a filling attached thereto by a part of its material extending into the perforation or perforations of said scalp or shell. 55

3. The collet on the verge-shaft carrying the pallets of the escapement and supporting the pendulums, as set forth.

4. Shell G, provided with an annular side 60 wall, in combination with pendulum-rod D, which has a flattened or angular part, D³, that passes through said side wall from top to bottom, to prevent the pendulum-ball from turning.

5. A pendulum-rod which is all in one piece, in combination with a shell or scalp, G, through the side walls of which it passes, said rod and the perforations in said scalp being of such shape as to prevent said shell from turning on said rod. 70

6. In combination with scalp G, the filling or body F, having pins f' f, which extend into holes g g of said scalp, said parts composing a pendulum-ball, substantially as described. 75

In testimony whereof I affix my signature in presence of two witnesses.

ARTHUR E. HOTCHKISS.
